UNITED STATES PATENT OFFICE

170,486

DOCUMENT COPYING MACHINE

Earl E. White and George J. Smith, Rochester,
N. Y., assignors to Eastman Kodak Company,
Rochester, N. Y., a corporation of New Jersey

Application July 24, 1952, Serial No. 20,748

Term of patent 14 years

(Cl. D61—1)

To all whom it may concern:

Be it known that we, Earl E. White and George J. Smith, citizens of the United States of America, residing at Rochester, in the county of Monroe and State of New York, have invented a new, original, and ornamental Design for a Document Copying Machine, of which the following is a specification, reference being had to the accompanying drawings, forming a part thereof, in which:

Fig. 1 is a front perspective view of a document copying machine showing our new design; and

Fig. 2 is a rear perspective view of the document copying machine shown in Fig. 1.

We claim:

The ornamental design for a document copying machine, as shown.

EARL E. WHITE.
GEORGE J. SMITH.
